UNITED STATES PATENT OFFICE.

HARRY CHILINGIRIAN, OF BRIDGEPORT, CONNECTICUT.

SAFETY COOKING AND BAKING STOVE.

Application filed May 22, 1924. Serial No. 715,099.

To all whom it may concern:

Be it known that I, HARRY CHILINGIRIAN, a citizen of Armenia, residing at Bridgeport, county of Fairfield, State of Connecticut, have invented a new and useful Safety Cooking and Baking Stove, of which the following is a specification.

This invention relates to cook stoves, and has for an object to provide an improved construction of stove for cooking purposes which may be closed when not in use to present a neat and attractive appearance, in which during the cooking and baking operations the articles are entirely enclosed to conserve the heat and prevent escape of gases and odors, and in which means is provided to prevent manipulation of the gas burner valves by small children.

With the foregoing and other objects in view, I have devised the construction illustrated in the accompanying drawings, forming a part of this specification, similar reference characters being employed throughout the various figures to indicate corresponding elements. In these drawings,

Fig. 1 is a perspective view of a stove constructed according to my invention, the stove being closed.

Fig. 2 is a transverse section thereof.

Fig. 3 is a partial longitudinal section and a partial front elevation.

Fig. 4 is a horizontal section substantially on line 4—4 of Fig. 5.

Fig. 5 is a transverse section through the gas burner portion of the stove.

Fig. 6 is a detail view showing one means of mounting the flexible closure.

Fig. 7 is a detail showing of the means for mounting the flexible closure.

Fig. 8 is a transverse section of the upper part of the stove showing a different type of closure.

Fig. 9 is a detail showing of the means for mounting the type of closure shown in Fig. 7 on an enlarged scale, and

Fig. 10 is a transverse section substantially on line 10—10 of Fig. 9.

Referring to Figs. 1 to 7 the stove comprises a bottom member 10, preferably of sheet metal, mounted on suitable supports, as the legs 11 of angle iron, the ends of the bottom member 10 being bent upon themselves, as shown at 12, for interlocking sliding engagement with similarly bent bottom

edges 13 of upright end walls 14. The upright edges of these end walls are bent upon themselves, as shown at 15, for interlocking sliding engagement with similarly bent upright edges 16 and 17 of front and rear walls 18 and 19 respectively. These walls form an enclosure or cabinet for the heating elements. Extending transversely of this cabinet is an upright wall 20 dividing the cabinet into two chambers 21 and 22. In the chamber 21 is mounted a grate 23 supported in any suitable manner, as by mounting it on bars 24, and the sides of the chamber are protected by fire brick 25. At the rear of this chamber the rear wall 26 does not extend to the top wall or support 27 for the articles to be heated, some of which are indicated in outline at 28, but this rear wall is bent downwardly, as shown at 29, to form a flue 30 for products of combustion and a rear wall for the ashpit 31. A pipe 32 leads from the lower part of this flue 30 to the usual chimney, and the usual damper 33 is provided to control the draft. This damper is operated from the front of the stove by a handle 34 by turning the rod 35 having an arm 36 connected to the damper by a rod 37. A suitable damper 39 is also provided in the front 38, and this front is preferably hinged as shown at 40. The usual lids 41 are provided in suitable openings in the top wall or support 27 over the fire box.

In the other chamber 22 are mounted fluid fuel burners 42, which may be for either liquid or gaseous fuel as desired, and suitable openings 43 are provided in the top or support 27 over the burners. Beneath these burners is a horizontal wall 44 forming an oven 45 beneath the burners, and in this oven are other burners 46. Suitable sliding shelves or supports 47 are provided in this oven for supporting the articles to be heated. A flue 48 controlled by a damper 49 leads from this oven to the smoke pipe 32 to carry off the vapors or products of combustion. This damper is similar to the damper 33 and may be operated by the same type of mechanism from a handle 50 at the front of the stove.

Extending along the front of the top or support 27 is a chamber 51 in which the fuel supply pipe 52 for the burners is located, and branches lead from the pipe to

the various burners controlled by the usual valves 53. These valves are also located in this chamber 51 and the top of this chamber is closed by a movable wall 54 hinged at 5 its rear edge, as shown at 55. This wall is also provided with perforations 56 to allow entrance of air for the gas burners and also air for hard fuel fire. The pipe 52 is connected to any suitable source of supply 10 by a pipe 57 which is preferably mounted in a space 58 at the outer end of the chamber 22 where it is protected and is also out of sight. It may if preferred be covered with asbestos or other suitable fireproof material 15 to protect it from the heat of the burners. It will be noted that in order to gain access to the gas control valves 53 the top wall 54 must be raised, as shown in Fig. 5.

The end walls 14 are extended a considerable distance above the top of the supporting wall 27, and they are connected at the rear of the stove by the upright rear wall 19, which also extends at a considerable distance above the top wall 27. The rear 25 wall 59 of the combustion chambers is spaced somewhat forwardly of the rear wall 19 to leave a space for the flexible closure 60. This closure is mounted to slide in suitable guides 61 carried by the end walls 14, and 30 these guides extend from a point at the front of the stove above the top wall 54 upwardly, backwardly, and downwardly into the space 58, as shown in Figs. 2 and 5. The flexible closure is preferably of corrugated sheet 35 metal, and in the corrugations of which are mounted rods 62 carrying at their ends rollers 63 running in the guides 61, these guides being preferably formed by a pair of rectangular bars 64 secured to the end walls 40 by any suitable means, such as rivets 65. At the front edge of the closure is a reinforcing bar 66 carrying suitable handles 67 for manipulating the closure. By lifting on these handles the front edge of the closure may 45 be raised and the closure brought to an upright position immediately in front of the rear wall 19 leaving the whole top of the stove open for easy access to the articles supported on the top wall 27. By pulling 50 forwardly and downwardly on the handles 67 this closure may be drawn to the position shown in Fig. 2 completely enclosing the top wall and the articles thereon in a chamber 68. This will tend to hold the 55 heat about these articles, and will also prevent the escape of vapors and odors from articles being cooked in the room, a suitable flue 69 being provided leading from the upper portion of this chamber to the smoke pipe 32 and controlled by a suitable damper 70. It will be noted that when this flexible closure is in the position shown in Fig. 2, or closed position, that the reinforcing bar 66 forming the front edge of the closure, 60 rests upon the top of the top wall 54 ef-

fectively preventing the raising of this wall by small children so that they cannot reach the gas control valves 53.

If desired a warming oven 71 may be supported above this flexible closure by the 70 rear and end walls, which may also be provided with suitable doors 72. It will be apparent from an inspection of Fig. 2, that heat from the chamber 68 will have easy access to the bottom wall 73 of this oven by 75 passing to the rear of the flexible closure.

In Figs. 8, 9 and 10, I have shown a slightly different construction of flexible closure. In this case instead of being of corrugated sheet metal it is a plain sheet of 80 flexible metal 74, and in one of the bars 75 forming the guide 76 for this closure are mounted a plurality of anti-friction rollers 77 on suitable pins 78 upon which the closure runs. Otherwise the operation of this form 85 is the same as in the first form.

It will be apparent from the foregoing description and from an inspection of the drawings that this stove will be neat and attractive in appearance, that when closed, 90 as shown in Figs. 1 and 2, the various devices are all enclosed where they are protected from dirt and injury, that access may be easily had to the burners and the top plate by merely lifting on the handles 67 95 to move the flexible closure to a position in front of the rear wall 19, and that if desired the articles may be enclosed during the cooking operation to prevent waste of heat and also escape of odors into the room. 100 When the closure is in the position shown in Figs. 1 and 2 access to the gas valve by small children is effectively prevented.

Having thus set forth the nature of my 105 invention, what I claim is:

1. In a cooking stove, heating means, a support for articles to be heated, end and rear walls forming an enclosing cabinet for the heating means, a closure movable to a position to leave the front open to allow access to said support and heating means and movable to a position to close the front of said cabinet, control means for the heating means, walls forming a chamber to enclose the control means, one of said walls being movable to allow access to the control means, and said movable closure being arranged to control the operation of the movable wall.

2. In a stove, a support for articles to be heated, heating means beneath said support, control means for the heating means, walls forming a chamber to enclose the control means, one of said walls being movable to expose said means, upright end walls and a 110 rear wall at the ends and rear of said support, curved guides carried by the end walls, and a flexible closure mounted in said guides and arranged to assume a position in front 115 of the rear wall to expose the articles on the 120

support or to be drawn over and downwardly in front of said articles to enclose the same, said flexible closure being arranged to control the operation of the movable wall.

3. In a stove, a support for articles to be heated, fluid fuel burners beneath said support, control valves for said burners, walls forming a chamber to enclose said valves, one wall of said chamber being hinged to allow access to said valves, upwardly extending end walls and a rear wall at the ends and rear of said support, curved guides carried by the end walls, and a flexible closure mounted in said guides, said closure arranged to assume a position in front of the rear wall to expose the articles to be heated and to be drawn over and down in front of said articles to enclose them, said closure when in the latter position arranged to secure said hinged wall in closed position.

4. In a stove, a support for articles to be heated, fluid fuel burners beneath said support, control valves for said burners, walls forming a chamber to enclose said valves, one of said walls being movable to expose said valves, a movable closure adapted to enclose said articles and to be moved to a position to expose them, said closure when in the first position arranged to retain the movable wall in closed position.

5. In a stove, a support for articles to be heated, fluid fuel burners beneath said support, control valves for said burners, walls forming a chamber to enclose said valves, the top wall being hinged to expose said valves, upright end walls and a rear wall at

the ends and rear of said support, curved guides carried by the end walls, a flexible closure mounted in said guides, said closure movable to a position in front of the rear wall to expose said articles and adapted to be drawn forwardly and down over said articles to enclose the same, the forward edge of said closure when in the latter position resting on the top of said hinged wall to retain it in closed position.

6. In a stove, walls forming an enclosed cabinet, a transverse upright wall in said cabinet forming separate combustion chambers, a grate for solid fuel in one of said chambers, fluid fuel burners in the other chamber, a horizontal wall forming an oven beneath said burners, a burner in said oven, control valves for said burner, walls forming a chamber to enclose said valves, one of said walls being movable to expose said valves, a flue for products of combustion leading from the solid fuel combustion chamber, a connection from the oven to said flue, upright end walls and a rear wall at the ends and rear of the top of said combustion chambers, curved guides carried by the end walls, a flexible closure mounted in said guides arranged to be moved to an upright position in front of the rear wall or over and downwardly to enclose said top wall and form a chamber above it, and a connection from said chamber to said flue, said flexible closure being arranged to control the operation of the movable wall.

In testimony whereof I affix my signature.

HARRY CHILINGIRIAN.
